MINING-MACHINE.

1,122,034.

Specification of Letters Patent. Patented Dec. 22, 1914.

Application filed January 7, 1903, Serial No. 138,158. Renewed June 4, 1909. Serial No. 500,123.

To all whom it may concern:

Be it known that I, FRANK L. SESSIONS, a citizen of the United States, residing at Columbus, in the county of Franklin and State of Ohio, have invented certain new and useful Improvements in Mining-Machines, of which the following is a specification, reference being had therein to the accompanying drawing.

10 The invention relates to side cutting mining machines and particularly to the type of machine which has an elongated cutter frame projecting from a suitable main frame and carrying suitable cutting mechanism, usually in the form of a cutter chain which moves in ways on the cutter frame.

One of the more important objects attained by the invention is the maintenance of the cutter bar at a suitable angle to the 20 face of the coal as the cutting proceeds. In machines of this character the best results are secured when the longitudinal axis of the cutter bar is maintained at about 90° to the coal face. As the force which advances the machine along the face of the coal is necessarily applied to the machine at points outside the body of the coal and as the major part of the resistance is offered by the coal against the cutters, the tendency is for the 25 outer frame part to advance faster than the cutter frame so that the latter swings backward and the machine is not held up to its work. By my invention the cutter frame is maintained at a proper angle to work effectively, either automatically or under the control of the machine operator.

Another object is the attainment of the above result without the use of tracks or other rigid guide devices for the machine.

40 Another object which is attained by my invention is the provision of a side cutting machine adapted to cut close to side ribs or walls so that the machine is fitted for room and pillar work.

45 The foregoing and various other objects of the invention will be understood from the following description which sets forth, in connection with the accompanying drawings, the features of construction, arrangements and combinations of parts in which 50 the invention consists.

Figure 1 is a plan view of a mining machine embodying my improvements. Fig. 1^a is a fragmentary view of a part of a cutter frame showing cutter bits that are reversible

though not automatically. Fig. 2 is a view partly in side elevation and partly in section, of the same. Fig. 3 is a side elevation. Figs. 4, 5 and 6 are diagrammatic plan views illustrating the mode of operating the machine. Figs. 7 to 21 show details. Fig. 22 is an elevation of the forward end of the machine, the side shown being opposite to that illustrated in Fig. 2.

The mechanism comprises what may be regarded as a bed, a cutting apparatus, an engine or motor, means for causing the movements of the machine bodily from place to place, power transmitting devices interposed between the engine or motor and the cutting apparatus, power transmitting devices interposed between the engine or motor and the transporting devices, and a framework upon which all of the operative parts are supported, and which in turn is supported upon the bed part.

A indicates the bed part as a whole; B the cutting apparatus; C the motor or engine; D the devices by which the machine is transported or moved from place to place; E the power transmitting devices for actuating the cutting device; F the devices which transmit power and motion to the machine-moving parts; and G the framework which carries all of the operative parts.

The bed or ground support consists of runners or shoe-like bars at a, one upon each side, with suitable cross bars as at a' for firmly holding together the side parts. The bars a, a' constitute a plate-like support 35 that adapts the machine for free movement in all directions over the ground or floor of the mine.

The cutting apparatus as illustrated consists of a chain H mounted in guideways 95 upon a frame indicated as a whole by I. In Figs. 1, 18 and 19, and also in Figs. 20 and 21, the chain shown is provided with automatically reversible cutter bits, while in Figs. 1^a and 3 the chain shown has a simpler form of bit which can be manually reversed when desired. In the case of the automatically reversing cutters, the bits are held in pivoted blocks which are adapted to swing so as to present one or the other of 100 the bits in operative position according to the direction of travel of the chain. The frame consists of the pivoted plate i and the part i', the latter having grooves at $\frac{1}{2}$ in which is fitted the outwardly extending part 110

MINING SURFACE CUTTING APPARATUS

2

1,122,084

i^3 of the pivoted plate. The pivotal portion at i is in a plane somewhat above that of the outer portion i' , so that the chain shall have clearance in traveling. At the outer end of the chain frame there is a sprocket wheel J . The two parts of the chain plate are adjustable, there being an adjusting screw at K which passes through a nut k in a recess in the part i^3 of the plate i , and bearing 10 against an abutment at i^4 on the outer part of the frame. The cutting apparatus is adapted to be swung in horizontal planes in either direction, as indicated in the drawings, and in the manner and for the purposes 15 to be described.

The motor shown at C is an electric motor, having a horizontally arranged armature and armature shaft c , provided with a pinion C' . The motor metal is so arranged as 20 to incase the commutator and the adjacent parts.

The framework G which is interposed between the bed and the operative parts and upon which the latter are directly mounted 25 comprises two parallel bearing plates L, L' , arranged one above the other and extending rearward from the main frame or the motor metal, and each having a vertically disposed flange, which is secured to the said main frame or motor metal by means of bolts. A supporting plate for the cutting apparatus at L^2 is extended forward from the rear part of the frame and is formed with an elongated tubular bearing l arranged vertically. M is a vertical shaft mounted in this bearing, preferably in a sleeve m fitted into the bearing part l . It carries a sprocket wheel N at its lower end with which engages the cutter chain. Near the upper end it has 30 a beveled wheel N' engaging with the aforesaid beveled pinion C' on the end of the motor shaft. The wheel N' being keyed rigidly to the shaft M it not only causes the rotation of the shaft, but also the motion of the 35 chain through its guideways in the frame.

The inner pivoting plate i of the chain frame is mounted on and turns around the sleeve l as a bearing. The shaft M is additionally supported at the upper end by means of the bearing plate L extending out from the frame or from the motor metal, as above described.

The means for transporting the machine from place to place consists of a rope or cable P having one end secured to a winding drum P' and extending thence around a sheave P^2 which is secured to some suitable stationary object, and having its other end fastened to a disk or plate P^3 . The latter 50 is of the nature of a peripherally grooved sheave of relatively large diameter. It is connected to the cutter chain frame in a suitable way so that as it turns in either direction said frame will be compelled to turn 55 with it. As shown, it is also connected to a

bracing ring or collar P^4 having a downwardly extending arm or flange p , and this arm and the sheave or wheel P^3 and the plate i of the chain frame are secured together by bolts at p' . Although I have 70 shown them bolted and separated, sheave P^3 and plate i may be all one casting. The winding drum P' is rotated by means of a gear wheel q with which engages a driving pinion q' on a shaft q^2 . The latter at one 75 end has a ratchet wheel Q' with which engages a pawl Q^2 carried by a radius arm Q^3 centered upon the shaft. The radius arm and pawl are reciprocated by a link Q^4 which is connected to a reciprocated frame 80 Q^5 held in a guide Q^6 . The frame is pivotally connected to the arm Q^7 of a ring Q^8 which fits an eccentric R at the upper end of the shaft M . At each rotation of the shaft the eccentric gives one reciprocation 85 to the part Q^5 and that in turn gives one feeding movement to the pawl and ratchet wheel.

S is a plate or bar the end of which lies near the points of the teeth on the ratchet 90 wheel Q' and also lies in the path of movement of the pawl Q^2 . This plate can be adjusted so that its end shall expose one, two or more of the teeth of the ratchet wheel, and in this way the extent of feed of 95 the machine will be controlled. If the plate S is so held that its end entirely prevents the pawl from engaging with the ratchet wheel, the advancing movement of the machine will be stopped. The pulley or sheave 100 P^2 , around which the rope passes, may be fastened to any suitable holder, such as a stake in the ground or floor of the mine, or it can be secured to an anchor in a wall of coal or rock, or to an upright or post secured in the proper place.

At either side of the machine are provided thrust bars T, T' , arranged to be pushed forward by projecting lug P^6 on disk P^3 , and pivoted at their ends to levers T', T^2 . Levers T', T^2 are rigidly mounted upon shaft T^4 which has bearings at T^5, T^6 , upon the frame G . Lever T^2 is carried above the point where bar T is pivoted to it and to this elongation is attached one end of spring T^6 and bar T^7 . The other end of spring T^6 is attached to the motor frame. The other end of bar T^7 is adjustably connected to bar S by means of a hand screw t . Spring T^6 tends to draw bar T^7 together with bar S 110 rearward so as to prevent the pawl Q^2 from engaging with the ratchet teeth. The ends of thrust bars T, T' lie in or nearly in the plane of rotation of the rope sheave or disk P^3 and the latter is provided with a lug P^8 115 which is adapted to strike against the end of the thrust bar and push it forward when the disk or sheave P^3 rotates far enough to bring them together, and at t' there is a hook on the bar T adapted to ride over, 120

125 130

drop behind and engage with a lug p^2 on the sheave. The lugs P^s and p^2 are so situated that they come into action at about the time that the cutter frame has reached the lines at right angles to the lines of advance of the machine as a whole. At about this time the hooked end of the bar T drops into engagement with the lug p^2 and the lug P^s lies adjacent to the end of the bar T . Thereafter, if the chain frame should swing rearward to an angle less than 90 degrees, it will tend to draw the bar T backward and to draw the bar or plate S over the ratchet and cut off some of the teeth from the action of the pawl Q^2 , and the feed of the machine will be reduced. The speed of the cutters will remain the same, however, and they will form a kerf relatively faster by reason of the reduced rate of feed. Consequently the cutter frame will swing forward in accordance with its constant tendency under the action of the chain-drive gearing in conjunction with the resistance of the coal to the travel of the cutters around the cutter frame. As the cutter frame thus swings forward the rate of feed effected by the pawl and ratchet devices is increased again and when the correspondingly increased resistance of the coal to the advance of the cutter frame balances the forces tending to swing the cutter frame forward, such swinging stops and equilibrium is thus again restored. Too great travel of bar T is prevented by so shaping its engaging end that it will automatically disengage when sheave P^s has rotated backward a predetermined amount. This disengagement is effected by the supporting stirrup T^s against which the raised portion T^s strikes when bar T is forced rearward. Bar T is held in engagement with lug p^2 by the spring p^s .

While, in the normal operation of the machine, the automatic operation above referred to is largely relied on, the machine operator can at all times have an optional control of the bodily advance of the machine and of the angular position of the cutter frame, by suitably adjusting the guard plate S in the bar T^s , such adjustment being effected by means of the hand screw t .

To prevent the winding mechanism P' from paying out cable when the cutter frame is dropping back from the carriage frame under excess of load, and also to lock the ratchet Q' against back rotation during the interval when the pawl Q^2 is disengaged from said ratchet so as to insure forward feed of the machine, I provide a stationary pawl W pivoted at w to a lug W' on the frame G . A spring w' secured to the frame G engages the under surface of the pawl holding it normally against the ratchet Q' . The thumb piece w^2 provides means for lifting the pawl off the ratchet to quickly stop the feed of the carriage frame. When the

pawl is drawn back the spring holds it against engagement with the ratchet as shown in dotted lines in Fig. 10.

It is frequently necessary to adjust the inclination of the cutting apparatus to the horizontal, it being sometimes requisite that the chain frame should move in a horizontal plane and at other times that it should be inclined in relation to the horizontal, or in relation to the ground line. To accomplish such adjustment, I provide the bed frame and the frame which supports the operative parts with devices for adjusting the latter by a tilting movement on the former. The two frames are hinged together at U , this being at a line near the rear end. At the front end there is a threaded lifting device consisting of a screw V which, at the lower end, is trunnioned or hinged at v to the bed frame. A double flanged nut V' engages with the motor frame G by means of a flange on the latter, and the adjustable nut V' permits the ends of the two frames to be separated or to be brought closer together, according as a greater or less inclination of the cutting apparatus to the ground line is desired.

The mode of operating a machine of the kind above described will be readily understood.

The mechanism is adapted for cutting coal either upon the room and pillar plan or upon the wall plan. The several important positions in the operation of undercutting a room in the room and pillar plan of cutting are illustrated in the diagrammatic views in Figs. 4, 5 and 6. In starting the operation in a room, the machine is placed as shown in Fig. 4, that is to say, close to one pillar wall with the cutting apparatus projecting away from this wall and with the framework parallel and close thereto. An anchor and pulley are temporarily fastened as shown in Fig. 4, and the machine is jacked down by screw braces which hold it firmly in position. Then the operative parts being put into action, the cutter chain is set in motion and simultaneously the rope-winding devices draw upon the rope and, pulling the latter around the anchor sheave, cause the cutter frame to swing against the coal face in the direction of the dotted lines in Fig. 4. As the cutters engage and cut away the coal to form a kerf, the cutter frame continues to swing in the direction stated under the action of two forces; one of these, of course, is the tension of the rope exerted on the cutter frame directly, and the other is due to the lever-like action of the driving pinion C' on the gear N' in connection with the resistance to the movement of the cutters around the cutter frame. The nature of this latter force will readily be understood if the resistance to the movement of the cutters is supposed to be great enough to pre-

95
100
105
110
115
120
125
130

1,122,034

vent such movement; then the cutter chain is in effect locked to the cutter frame and the driving effort of the pinion C' tends to swing the frame like a lever. Obviously any lesser resistance to the travel of the cutters will be accompanied by a similar though correspondingly weaker leverage action by the drive gear on the cutter frame. After the cutters have penetrated the coal sufficiently to reach the rib or pillar line the cutting is stopped and the machine is turned into the position shown in Fig. 5. The anchor and its sheave are now placed near the opposite rib or pillar wall. The cutters are reversed in the cutter chain, either automatically or by hand, according to the form of cutter used, and the rope is secured to the opposite side of the sheave or disk P³. Power is again applied to the machine, and the cutting action is continued across the face of the room. During this action novel and peculiar results are obtained with respect to the action of the feeding apparatus, the advance of the machine as a whole, and the control of the angular position of the cutter frame in relation to the face of the coal. As the machine advances along the face of the coal it is, as an entirety, subject to the following main or controlling forces, namely, the tension of the outside run of the rope P acting on the main frame of the machine; the tension of the inside run of the rope P, the direct action of which is on the cutter frame of the machine; the rearward reaction of the coal at X against the cutters; and the inward reaction of the coal on the cutter bits. Now it will be understood that the advance of the cutter frame structure along the face of the coal so as to undercut the seam, and the maintenance of the cutter frame structure in a suitable angular relation to the face of the coal for a proper performance of its functions, is the ultimate object sought, and it is therefore important to note the main or controlling forces to which the cutter frame, including parts which under conditions of operation can be considered as more or less rigid with the cutter frame proper, is subjected; in some machines the cutter frame proper is pivotally connected with a main frame part, as in the present case, while in other machines the cutter frame proper and the main frame part are rigidly united, but in either case the movements of the cutter frame proper are determined by the main or controlling forces to which the rigid structure, including the cutter frame proper, is subjected. In my improved machine the main forces acting upon the cutter frame structure (including the cutters, the sprocket wheel N, the shaft M and the gear N') are the rearward reaction of the coal on the cutters which tends to swing the cutter frame rearward, the inward reaction of the

coal on the cutter bits which tends to draw the cutter frame inward and therefore to hold the machine up to its work, the forward draft of the inside run of the rope P which tends to swing the inner end of the cutter frame forward, the forward pull of the main frame on the cutter frame through the shaft M, and the force of the driving pinion C' which tends, by reason of the resistance to the travel of the cutters, to swing the main or inner part of the cutter frame forward. The inward reaction on the cutters acts always advantageously by tending to hold the machine up to the coal face and it need not be further considered. The remaining forces acting on the cutter frame structure determine its advance along the face of the coal and its relative angular position with respect to the face, and it is the peculiar control of these forces which largely characterizes my present invention. The rearward reaction of the coal on the cutters will obviously vary with the hardness or density of the coal. Thus, if the resistance to the advance of the cutter frame increases beyond what may be considered a normal value, the tendency is for the cutter frame to swing relatively backward, that is, to an angle less than 90° to the longitudinal line of the machine. When it is thus swung backward, by reason of the corresponding movement of the lug P⁶ which lies adjacent the rear end of the thrust bar T, the spring T¹ is free to draw the guard plate S backward so as to prevent the pawl Q² from engaging with one or more or even all of the teeth of the ratchet wheel Q' which the pawl would otherwise engage in its normal stroke. Of course, if the hook t' on the end of the bar T had been engaged with the adjacent lug p², the rearward movement of the bar T is assured by such positive engagement as well as by the action of the spring T¹. This movement of the guard plate S more or less backward results in a corresponding retardation of the forward feed of the machine. This retardation of the machine's advance permits the cutters, which are in continuous action, to form the kerf more rapidly in relation to the advance of the machine so that the cutter bar is again gradually swung forward toward its normal angular position in relation to the face of the coal, the cutters being held up to their work during such swinging of the cutter frame by the combined action of the tension of the inner run of the rope P and the leverage action of the drive pinion C' previously explained, or by this last named leverage action alone, in case the automatic adjustment of the plate S had been such as to stop the forward feed of the machine as an entirety. As the cutter frame approaches in its forward swing the normal angular position, the lug P⁵ on the rope sheave or disk P³ engages

the end of the thrust bar T and the latter is caused to push the bar S forward somewhat so that the pawl can again reach one or more of the teeth on the ratchet wheel and thereupon the forward feeding of the machine at its more normal rate is resumed.

The control of the advance and angular position of the cutter frame above described is, of course, wholly automatic; but it will be understood that the machine operator can at any time have an optional control of the position of the guard plate S by means of the hand screw *t* and can, therefore, control at will the advance of the machine as an entirety and the angular position of the cutter frame in relation to the coal face. This optional manual control of the machine is available while the machine is advancing and working, as in the case of the automatic control, and is especially advantageous when obstructions of an unusual nature are encountered by the cutters as it enables the machine operator to handle the machine in the most advantageous manner in each case.

It may be remarked that the action of the feed rope upon the machine is differential in its nature by reason of the fact that the outside run of the rope exerts its draft directly on the main frame parts while the inside run of the rope exerts its draft on the cutter frame which is pivotally connected to the main frame, thus, when the rearward reaction of the coal on the cutter frame increases, the feed rope tends to advance the main frame more rapidly than the part of the cutter frame to which the inside run of the rope is connected; or, in other words, the cutter frame tends, under such conditions, to swing rearward. In all cases when the feed rope devices are in operation their preponderating effect, in conjunction with the rearward reaction of the coal, is to swing the cutter frame rearward, although the draft of the inside run of the feed rope on the cutter frame acts in conjunction with the drive pinion C' with a tendency to swing the cutter frame forward. The adjustment of the guard plate S, either automatically or manually, as described above, effects, it will be seen, a relative variation of the forces tending to swing the cutter frame rearward and forward, respectively; and it is by such relative variation of these forces that the angular position of the cutter frame in relation to the coal face is controlled as the machine advances in its work.

When, in the process of undercutting the seam, the machine has approached as near as possible to the left pillar wall of the room, it is stopped and moved into the position shown by full lines in Fig. 6. The main frame having then been jacked down, the motor is started and the cutter frame 55 swung around to the left, as indicated by

dotted lines, to complete the cut. This swinging of the cutter frame is effected, as will readily be understood, by the combined action of the draft of the rope P and by the leverage action of the chain driving gears 70 upon the cutter frame.

It will now be readily understood that the control of the advance and angular position of the cutter frame as the machine moves along the face of the coal, the manner of 75 making the entering or sumping cut at one rib or pillar wall and of completing the undercut at the other pillar wall and various other possible manipulations of the machine, are all intimately connected up with and 80 more or less dependent upon the capacity of the main frame for universal movement over the mine floor. It will be seen further that the connection of the draft rope to the machine at a point or points close to the 85 coal face helps to hold the machine up to its work. This construction and arrangement of the draft rope devices, the capacity of the cutter frame to yield or swing rearward and then regain its normal position, 90 and the inward reaction of the coal on the cutter bits tending to hold the rear end of the machine up to the face, are features which in their combined action make possible the operation of the machine without 95 the use of tracks or other rigid guide devices.

I am aware that swinging cutter frames held by vertical pivots to the main frame have heretofore been used or proposed but in 100 all such cases within my knowledge the machines differed from my present invention in that provision of one sort or another was made for having the swinging cutter frame locked in its operative position in relation 105 to the main frame. I am also aware that it has been proposed to arrange draft devices, such as cables or chains, so that they should extend forward from a winding mechanism on the main frame around the stationary 110 sheave or anchor and thence back to the laterally extending cutter frame; but this was done in machines of the character above referred to in which the cutter frame was rigidly locked in operative position to the 115 main frame, and therefore the basic and principal purpose that I accomplish was not attainable, namely, the automatic feeding of the cutter frame into the coal and the automatic balancing of stresses when the cutter 120 frame (without any positive lock or stop,) is capable of swinging backward and forward in relation to the main frame. I am also aware that it has been proposed in the case of a machine with a main frame and a 125 rigidly connected cutting apparatus, to interpose between the feeding and controlling mechanism and the machine proper, a friction connection of such a nature as to permit slippage, as, for instance, in the patent to 130

Kangley, No. 435,426, and also in the patent to Mitchell, No. 656,414; but in my machine it is preferred to give the cutter frame a capacity for yielding or swinging rearward 5 and subsequently regaining its normal angular position as the conditions change, as well as to provide for a variable feed of the machine as an entirety.

Of course it will be understood that in 10 many respects there can be modification as concerns the details of the parts shown without departing from the essential features of the invention.

What I claim is:—

15. 1. In a mining machine, the combination of a main frame, a cutter-carrying frame carried by the main frame but free to move thereon during the cutting operation, cutters thereon traveling in lines transverse to 20 the travel of the main frame, and a feeding mechanism having two independent points of connection with the machine, one on the main frame, and one on the cutter-frame, means for actuating the cutters and the feeding 25 mechanism simultaneously, and means for automatically throwing out of action the feeding mechanism, substantially as set forth.
2. In a mining machine, the combination 30 of the main frame, means for moving the said frame bodily on the ground, a cutter-carrying frame pivoted on the main frame and free to move about its pivot during the cutting operation, and means, supplemental 35 to said main frame moving devices, for moving the cutter frame relative to the main frame.
3. In a mining machine, the combination 40 of the main frame, a cutter-carrying frame thereon and movable relatively thereto during the cutting operation, a feeding mechanism for advancing the cutter-carrying frame, a supplemental feeding mechanism and means actuated by the cutter-carrying 45 frame for throwing the supplemental feeding mechanism out of action, substantially as set forth.
4. In a mining machine the combination 50 of a main frame, a cutter carrying frame pivoted thereon and adapted to assume different angles of inclination to the line of movement of the main frame, it being free to change its positions during cutting operations under the different conditions of resistance offered to the cutters, a feeding mechanism for operating the cutters, and mechanism for advancing the main frame and for holding the cutter frame up to its working position, substantially as set forth.
60. 5. In a mining machine, the combination of a main frame arranged to be moved along the ground, a cutter frame connected to said main frame to swing about a vertical axis, a motor mounted on said main frame, a 65 flexible draft device arranged to pass around

a fixed support and to have one end connected to said cutter frame and its other end connected to said main frame, a winding mechanism on said main frame for winding up said flexible draft device, power transmitting mechanism interposed between said motor and said cutter frame, power transmitting mechanism interposed between said motor and said winding mechanism, and means controlled by the position of said cutter frame relative to the main frame for connecting and disconnecting said last described train of power transmitting mechanism.

6. In a mining machine, the combination 80 of a main frame arranged to travel along the ground, a cutter frame connected to said main frame to swing about a vertical axis, a motor on the main frame, a winding mechanism thereon, a train of power transmitting devices interposed between said motor and said winding mechanism, a train of power transmitting devices interposed between said motor and said cutter frame, an endless draft device arranged to extend around a 85 fixed support or jack and to have one end connected to said winding mechanism and its other end connected to said cutter frame, and mechanism for throwing said winding mechanism into and out of operation controllable by said cutter frame in accordance 90 with its inclination to the main frame.

7. In a mining machine, the combination 100 of a bed frame arranged to travel along the ground, a motor mounted thereon, a cutter frame connected to said main frame to swing about a vertical axis, a cutter carrying chain on the cutter frame, power transmitting mechanism interposed between said motor and said cutter carrying chain, a 105 winding drum, variable feed mechanism interposed between said winding drum and said motor, a flexible draft device arranged to extend around a fixed support or jack and to have one end connected to said winding 110 drum and its other end connected to said cutter frame, and means automatically actuated by said cutter frame in accordance with its inclination to the main frame for throwing said feeding mechanism into or out of 115 operation.

8. In a mining machine, the combination 120 of a main frame, a cutter frame movably mounted on the main frame, cutters operatively mounted on the cutter frame, a motor for driving the cutters, feeding mechanism for advancing the main frame and for moving the cutter frame relative to the main frame, and means operable by the movement 125 of the cutter frame relative to the main frame for varying the rate of speed of the main frame, substantially as set forth.

9. In a mining machine, the combination 130 of a main frame, a cutter frame movably mounted on the main frame, cutters opera-

- 5 operatively mounted on the cutter frame, a motor for driving the cutters, feeding mechanism for advancing the main frame and for moving the cutter frame relative to the main frame, said mechanism comprising a power driven differential propelling means operatively engaging the main and cutter frames and a stationary abutment, and means operable by the movement of the cutter frame relative to the main frame for varying the rate of feed of the main frame, substantially as set forth.
- 10 10. In a mining machine, the combination of a main frame, a cutter frame mounted thereon to swing about a vertical axis, cutters operatively mounted on the cutter frame, a motor for driving the cutters, feeding mechanism for advancing the main frame and for moving the cutter frame relative to the main frame, and means operable by the movement of the cutter frame relative to the main frame for varying the rate of feed of the main frame, substantially as set forth.
- 15 11. In a mining machine, the combination of a main frame, a cutter frame mounted thereon to swing about a vertical axis, cutters operatively mounted on the cutter frame, a motor for driving the cutters, feeding mechanism for advancing the main frame and for moving the cutter frame relative to the main frame, said mechanism comprising a power driven differential propelling means operatively engaging the main and cutter frames and a stationary abutment, and means operable by the movement of the cutter frame relative to the main frame for varying the rate of feed of the main frame, substantially as set forth.
- 20 12. In a mining machine, the combination of a main frame, the cutter frame connected to said main frame to swing about a vertical axis, cutters carried by said last named frame, a motor mounted on said main frame, a flexible draft device arranged to pass around a fixed support and to have one end connected to said cutter frame and its other end connected to said main frame, a winding mechanism on said main frame for winding up said flexible draft device, power transmitting mechanism interposed between said motor and said cutters, power transmitting mechanism interposed between said motor and said winding mechanism, and means controlled by the movement of the cutter frame relative to the main frame for varying the speed of the winding mechanism, substantially as set forth.
- 25 13. In a mining machine, the combination of a main frame adapted in operation to rest upon and slide in all directions over the mine floor, a cutter frame extending therefrom, means for advancing the main frame and cutter frame which tends in conjunction with the rearward reaction of the
- 30 coal to swing the cutter frame in one direction relative to the coal face, means for applying to the machine a force, other than the reaction of the coal on the cutters, which is adapted to swing the cutter frame in the opposite direction, and manual means on the machine for relatively varying the actions of the respective aforesaid means, whereby the angular position of the cutter frame in relation to the coal face can be controlled as set forth.
- 35 14. In a mining machine, the combination of a main frame adapted in operation to rest upon and slide in all directions over the mine floor, a cutter frame extending therefrom, means for advancing the main frame and cutter frame which tends in conjunction with the rearward reaction of the coal to swing the cutter frame in one direction relative to the coal face, means tending to swing the cutter frame in the opposite direction, devices for automatically relatively varying the actions of the said means, and manual means for relatively varying the actions of the said means, whereby the angular relation of the cutter frame to the coal face can be controlled automatically manually as the machine advances, substantially as set forth.
- 40 15. In a mining machine, the combination of a main frame, a cutter frame extending therefrom, means for advancing the main frame and cutter frame which tends in conjunction with the rearward reaction of the coal to swing the cutter frame in one direction relative to the coal face, means operating independently of the advance of the main frame tending to swing the cutter frame in the opposite direction, and devices for automatically relatively varying the actions of the said means, whereby the cutter frame is maintained at a suitable angle to the coal face as the machine advances, substantially as set forth.
- 45 16. In a mining machine, the combination of a main frame, a cutter frame extending therefrom, means for advancing the main frame and the cutter frame which tends in conjunction with the reaction of the coal to swing the cutter frame in one direction relative to the coal face, means operating independently of the advance of the main frame for applying to the machine a force, other than the reaction of the coal on the cutters, which is adapted to swing the cutter frame in the opposite direction, and devices on the machine for relatively varying the actions of the aforesaid means, whereby the cutter frame can be maintained at a suitable angle to the coal face as the machine advances.
- 50 17. In a mining machine, the combination of an outer main frame part adapted to move along the face of the coal, an inner

elongated cutter frame part carried by the main frame and adapted to extend within the body of the coal, feeding mechanism for advancing the machine along the face of the coal, and means on the machine operable at will for varying the rate of advance of the inner end of the cutter frame in relation to the rate of advance of the outer end thereof, whereby the angular position of the cutter frame in relation to the coal face can be controlled at will as the machine advances.

18. In a mining machine, the combination of an outer main frame part adapted to move along the face of the coal, an inner elongated cutter frame part carried by the main frame and adapted to extend within the body of the coal, feeding mechanism for advancing the machine along the face of the coal, and automatic means for varying the rate of advance of the inner end of the cutter frame in relation to the rate of advance of the outer end thereof, whereby the angular position of the cutter frame in relation to the coal face is controlled as the machine advances.

19. In a mining machine adapted to room and pillar work, the combination of an elongated main frame, an elongated swinging cutter frame extending from one end of said main frame, a chain mounted on said cutter frame so as to be driven in either direction, cutters on the chain adapted to reverse automatically when the direction of the travel of the chain is reversed, a motor on the main frame for driving the cutters, and mechanism driven by the motor for swinging the cutter frame in one direction under the coal to a position closely adjacent and substantially parallel to one of the ribs, the main frame and cutter frame being pivotally connected whereby the former may be swung to a position parallel to the face of the coal to make the cross-cut in a direction opposite to that in which the cutter frame was first swung, and the mechanism for swinging the cutter frame being operable by the motor to swing said frame in either direction relative to the main frame, whereby in finishing the undercut adjacent a rib, the cutter frame can be swung in a direction opposite that in which it was swung in starting the cut, so as to carry the cut out to the line of the rib.

20. In a mining machine adapted to room and pillar work, the combination of an elongated main frame, an elongated swinging cutter frame extending from one end of said main frame, a chain mounted on said cutter frame so as to be driven in either di-

rection, cutters on the chain adapted to be reversed, a motor on the main frame for driving the cutters, and mechanism driven by the motor for swinging the cutter frame in one direction under the coal to a position closely adjacent and substantially parallel to one of the ribs, the main frame and cutter frame being pivotally connected whereby the former may be swung to a position parallel to the face of the coal to make the cross-cut in a direction opposite to that in which the cutter frame was first swung, and the mechanism for swinging the cutter frame being operable by the motor to swing said frame in either direction relative to the main frame, whereby in finishing the undercut adjacent a rib, the cutter frame can be swung in a direction opposite that in which it was swung in starting the cut, so as to carry the cut out to the line of the rib.

21. In a mining machine, the combination of a main frame constructed to rest upon and slide freely in all directions over the floor of the mine, a cutter frame extending therefrom, means for advancing the main frame and cutter frame which tends in conjunction with the rearward reaction of the coal to swing the cutter frame in one direction relative to the coal face, means tending to swing the cutter frame in the opposite direction, and devices for automatically relatively varying the actions of the said means, whereby the cutter frame is maintained at a suitable angle to the coal face as the machine advances, substantially as set forth.

22. In a mining machine, the combination of a main frame constructed to rest upon and slide freely in all directions over the floor of the mine, a cutter frame extending from the main frame, means for advancing the main frame and the cutter frame which tends in conjunction with the rearward reaction of the coal to swing the cutter frame in one direction relative to the coal face, means for applying to the machine a force, other than the reaction of the coal on the cutters, which is adapted to swing the cutter frame in the opposite direction, and devices on the machine for relatively varying the actions of the aforesaid means, whereby the cutter frame can be maintained at a suitable angle to the coal face as the machine advances.

In testimony whereof I affix my signature in presence of two witnesses.

FRANK L. SESSIONS.
